UNITED STATES PATENT OFFICE

2,630,200

COIN SELECTOR

Louis F. Hehn, Chicago, Ill., assignor to Mills
Industries, Incorporated, Chicago, Ill., a corpora-
tion of Illinois

Application December 30, 1946, Serial No. 719,263

2 Claims. (Cl. 194—101)

1

This invention relates to improvements in a coin selector for separating genuine coins of a single denomination from all other coins, slugs and checks. Although the present invention is directed primarily to a device to be used in connection with coin-controlled mechanisms which are operated by the insertion of United States nickels, the device is also adaptable for the selection of coins of other denominations and may be used without a controlled mechanism as a means for accomplishing the rapid separation of coins of a single denomination from a mixture of coins of assorted denominations.

Effective prior devices of this character have delicate parts incorporated therein which have a tendency, through use, to become improperly adjusted and are adversely affected by slight wear or the presence of small amounts of dust or dirt. The frequent servicing and adjustment of the devices, a necessity with such constructions, has heretofore required the inconvenient and time-consuming removal and disassembling of at least a part of the mechanism. The means for detecting and separating perforated coins, usually comprising the most delicate of the parts, have particularly been found to require the repeated attentions of servicemen.

Another inconvenience commonly experienced in the use of said prior devices has been the difficulty in removing coins which have become jammed or have been otherwise improperly retained therein. This difficulty frequently occurs in constructions which utilize magnets to influence the progress of coins through the device and in those which use a hooking means to restrict the passage of perforated coins. In the former design, coins and slugs of ferromagnetic material and underweight coins of paramagnetic material often adhere to the faces of the magnets disposed adjacent to the coin passages thus blocking said passages. In the latter design, difficulty is experienced when perforated coins fail to fall free of the hooking means. When either of these conditions occur, or when an imperfect coin becomes jammed in a passage within the devices of prior construction, the aid of a serviceman is often required to remove the coin, the mechanism being inaccessible to the operator. The removal of such coins not infrequently requires a partial disassembling of the mechanism.

To overcome the above mentioned undesirable characteristics and difficulties inherent in prior designs, I have devised the present coin selector device, an object of my invention being to provide in a simple and durable mechanism, the internal parts of which are readily accessible for cleaning, inspection and adjustment, the means whereby genuine coins of a desired denomination may be effectively and accurately separated from all coins, slugs and checks which are of incor-

2

rect size or weight, or are of counterfeit material.

Another object of the invention is to provide in a device of this character a durable and uncomplicated means, requiring no periodic adjustment, for detecting and retaining perforated coins.

A further object of my invention is to provide a means for preventing underweight coins from gaining entrance to the interior coin passages within such a device.

Still another object of my invention is to provide in a device of this character means by which the operator may easily clear the device mechanically of all coins retained within the interior of the mechanism, thereby avoiding the difficulties usually resulting from the jamming or the blocking of the coin passages within coin selecting or separating devices.

Other objects and advantages of the invention will be apparent from the following description of a preferred embodiment thereof, taken in connection with the accompanying drawings, in which:

Figure 1 is a front elevational view of a coin selector embodying the invention;

Figure 2 is a vertical section of the same taken substantially on line 2—2 of Figure 1;

Figures 3, 4 and 5 illustrate a vertical section taken substantially on line 3—3 of Figure 1 showing the action of the perforated coin retainer which is shown in different positions in the respective views;

Figure 6 is a rear elevational view of the device;

Figure 7 is a rear view partially cut away to show the action of the scavenger lever and sweep-arm;

Figure 8 is a section taken substantially on line 8—8 of Figure 6;

Figure 9 is a section taken substantially on line 9—9 of Figure 7;

Figure 10 is a front elevational view of the device in the opened position showing the trajectories of the coins;

Figure 11 is a side view taken on line 11—11 of Figure 10 and showing a means for mounting the device;

Figure 12 is a front elevational view of the underweight coin rejector;

Figure 13 is a side view of the same;

Figure 14 is a top plan view thereof;

Figure 15 is an enlarged section taken on line 15—15 of Figure 12; and

Figure 16 is a similar view showing the action of the underweight coin selector trap.

Referring in detail to the said drawings, a typical coin selector constructed in accordance with the present invention is built upon a fixed vertical plate 1, which may be securely mounted upon a supporting plate 90, or upon a coin op-

erated device (not shown), by means of screws 51 and spacer rods 52 (see Figs. 2 and 11).

In connection with the plate 1 various members form a series of thin, flat passages beginning with a passage 4 having an inlet portion 3 (see Figs. 2, 9 and 10). A coin, after having passed through said inlet 3 will drop onto an inclined coin rail 9 which forms a part of the bottom of the coin passage 4 extending laterally and downwardly from a point below the inlet opening 3. In reaching the coin rail 9 the coin passes through the magnetic field of a horseshoe magnet 10 which is mounted behind the plate 1 in a manner hereinafter described.

Coins of ferromagnetic materials are stopped and held in the magnetic field of the magnet 10, but coins of paramagnetic and diamagnetic materials pass unhindered through the magnetic field and roll down the coin rail 9, passing an undersize coin rejecting means to be later described. A coin not rejected by the undersize coin rejector will roll down the full length of the coin rail 9 and jump an open space onto an inclined surface 11 on a head portion 12a of a sweep arm 12 (see Fig. 10). The surface 11 thus forms a bottom for the lower portion of the coin passage 4.

Rolling off of the lower end of the surface 11, the coin will drop into a coin passage 5 (see Figs. 3-5 and 10) and will therein come into contact with a device for retaining perforated coins, to be hereinafter described. If the coin is unperforated, it will drop unhindered past this device and fall against an inclined track 14 formed by an inturned flange on a plate 14' which is adjustably mounted to the plate 1 by means of a screw 16 which passes through a slot 15 (see Fig. 6) in the plate 14' and is threaded into said plate 1.

Upon contacting the track 14 the coin will change its direction of travel and will follow an inclined passage 6 defined by track 14 on one side and an edge surface 13 of the sweep arm 12 on the other (see Fig. 10). The width of the passage 6 may be adjusted to be slightly greater than the diameter of coins of the desired denomination by adjusting the position of the plate 14' on the mounting screw 16. An oversize coin may thus be prevented from entering the coin passage 6 and will be rejected from the device by means hereinafter described.

A coin of the proper size will pass downwardly and laterally through the magnetic field of two opposed horseshoe magnets 17 and 18 which are attached by screws to the vertical plate 1 and to a front plate 2, respectively, the latter plate being hinged to the former as will be herein-after more fully described.

Having passed through the field of the magnets 17 and 18, the coin will fall onto a bounce block 20 secured by a screw 26 to the plate 1. The screw 26 may be threaded into said plate 1 or may be held by a nut 26a on the rear side of the plate.

The falling speed of a coin of paramagnetic material will be retarded as it passes through the magnetic field of the magnets 17 and 18 and this will reduce the amount of bounce resulting when such coin strikes the bounce block 20. In bouncing from the surfaces of the bounce block, the coin will again pass into the magnetic field of the magnets 17 and 18, which will still further reduce the inertia of the coin.

A barrier 27 is provided beyond the bounce block and its position is such that coins of counterfeit material, which are more affected by the magnetic field than coins of genuine material,

will fail to bounce over the barrier and will fall into a coin rejection passage 7 following a trajectory indicated by an arrow 7a in Figure 10. The barrier 27 comprises an angle piece having a vertical part 27a in which there is a slot 27b through which a screw 28 extends to adjustably secure the barrier to the plate 1.

Referring now particularly to Figures 6, 7, 10 and 11, two ears 29 are formed on the top of the plate 1 and have openings therein for receiving a hinge pin 30. The front plate 2 is hinged to said pin by means of ears 31 on the upper end of said plate, which upper end is of reduced width as compared with the lower part of the plate. Said front with the vertical plate 1, forms the sides for the coin passages above mentioned.

Mounted upon the front plate 2 is the above mentioned device for arresting perforated coins, said device being best illustrated in the Figures 1, 3, 4 and 5 and being more fully described below. The horseshoe magnet 18, an undersize coin return guide or chute 32, and a cam roller 33 mounted upon the guide by means of a bracket 34, best illustrated by Figure 9, are also carried by said front plate. The latter may be manually lifted to the open position shown in Figure 10, thus conveniently exposing all of the internal parts of the device for cleaning and adjustment.

In its normally closed position, as illustrated by Figure 1, the front plate 2 is held closed by the mutual attraction of the two magnets 17 and 18, the faces of which are exposed to the coin passage 6 through appropriate openings in the fixed vertical plate 1 and the front plate 2. This use of the attraction of the magnets 17 and 18 eliminates the need for any mechanical fastening means to hold the front plate in a closed position.

The barrier 27 acts as a stop for said front plate in its closed position and separates it from the fixed plate 1 a distance slightly greater than the thickness of a U. S. nickel or other predetermined coin. Side flanges 35 and 36 are formed on the front plate 2 and extend at right angles to the surface of said plate, the space between the flanges 35 and 36 being slightly greater than the horizontal measurement across the plate 1 so that, when the front plate 2 is in its operative closed position, said flanges constitute side walls of the selector device.

Also hinged to the pin 30 is a yoke 37 (see Figs. 6 and 7) which is held against the back of the plate 1 by means of a torsion spring 38 mounted on said pin with one end secured to the latter and the other end disposed in an opening in one leg of said yoke. The horseshoe magnet 10 is riveted or otherwise fastened to the yoke 37 by means of brackets 39 and is thus movable therewith. The coin rail 9, which is an integral extension of the central part of the cross-bar of the yoke 37, protrudes through a slot 40 in the fixed plate 1 and constitutes the bottom of the coin passage 4, as previously stated. A cam roller 41 is mounted upon one leg of said yoke 37, as best illustrated by Figure 6, its purpose being hereinafter explained.

The undersize coin return chute 32 is secured, as by rivets 41', to the front plate 2 (see Figs. 1 and 10) and the lower portion of said chute extends through an opening 42 in said plate. When the said front plate 2 is in its closed position, the lower portion of said chute 32 and the cam roller 33 mounted thereon extend through

an opening 43 in the fixed plate 1, as shown in Figure 2.

The upper portions of the plates 1 and 2 are formed so that, when said plates are in their normal vertical positions, said upper portions slope approximately ten degrees from the vertical, as best illustrated by Figure 2. A coin inserted into the coin passage 4 and dropping to the coin rail 9 will therefore lean against the upper portion of the plate 1 as such coin, if not held by the field of magnet 10, rolls down said rail 9.

In rolling along said rail, the coin will reach a point opposite a C shaped opening 44 in the plate 1 (see Figs. 2, 9 and 10). That portion of the plate 1 which forms the inside of the C is bent back to form an upwardly inclined shelf 45. The distance from the coin rail 9 to the uppermost point in the opening 44, indicated by the numeral 46 in Figure 2, is slightly less than the diameter of a U. S. nickel. Thus, if the diameter of a coin rolling down the coin rail 9 is greater than the distance from coin rail 9 to the point 46, the coin will roll past the opening 44 and continue on its course through the coin selector assembly. However, if the diameter of the coin is less than the measurement from the coin rail 9 to the point 46, the coin, upon reaching the opening 44, will fall over onto the shelf 45, the lower edge of the coin will slip off of the coin rail 9 and the coin will fall into the undersize coin chute 32 and slide out through the back of the coin selector assembly and into a reject chute 47 as illustrated by the arrows in Fig. 2. Coins, after dropping through said chute 47, will be directed by a guide 85 to a rejected coin receptacle (not shown). In this manner all undersize coins are rejected as such coins pass through the coin passage 4.

A retaining device for perforated coins is mounted on the front plate 2 by means of a bracket 48 riveted or otherwise secured to the plate 2 (see Figs. 1 and 3-5). Hinged to the bracket 48 by means of a pin 49 is a hollow frame 50 to the lower part of which is pivotably secured, by means of a pin 51, a finger member 52. On one end of this member an actuating finger 53 and a retaining finger 54 are formed, and in the other end there is a counterweight 55. The finger member 52 is so mounted that either the actuating finger 53 or the retaining finger 54, or both together, may protrude into the coin passage 5 through a slot 56 in the front plate 2. In the ready position, as illustrated by Figure 3, the counterweight 55 causes the member 52 to pivot on the pin 51 so that the retainer finger 54 is withdrawn from the coin passage 5 and the actuating finger 53 blocks said passage.

As an unperforated coin, indicated by the numeral 57 in Figure 5, drops through the coin passage 5, the lower edge of the coin will strike the actuating finger 53 and cause the member 52 to pivot on the pin 51 until the retainer finger 54 strikes the coin near its center. The continued movement of the coin through the coin passage 5 forces the actuating finger 53 completely out of said coin passage, allowing the coin to pass unhindered. The complete withdrawal of the actuating finger 53 is made possible by the pivoting of the frame 50 about the pin 49 as illustrated by the Figure 5. The lower edge of a perforated coin, indicated by the numeral 58 in Figures 3 and 4, in passing through the coin passage 5, will strike the actuating finger 53 which will cause the member 52 to pivot sufficiently on the pin 51 to cause the retainer finger 54 to enter the perfora-

tion of the coin, thus catching and retaining the coin, as illustrated by Figure 4, and preventing its further passage through the device.

The device of the invention includes a scavenging mechanism comprising a lever 59 having a horizontal portion 59' in the form of a finger piece accessible to the operator and a vertical portion 59a having a bifurcated lower end forming a fork 63 engaging a pin 65 on a crank arm 66 on a shaft 64 on which the sweep arm 12, above mentioned, is carried (see Figs. 1, 6 and 7). The lever 59 is rotatably mounted upon a shaft 61 which is fixed upon the back side of the supporting plate 1. One side of said lever 59 is formed into a cam 62 upon which rides the roller 41 on the yoke 37. The crank arm 66 and the sweep arm 12 are fixedly mounted, by pin or otherwise, to said shaft 64 which passes through the plate 1, the crank arm 66 being mounted on said shaft 64 on the back side of the plate 1 and the sweep arm 12 being mounted on the forward side of said plate. The crank arm 66 has on one side thereof a cam 60' engaging the roller 33 which is mounted on the lower portion of the undersize coin return chute 32 as before explained. Said cam engages said roller after the crank arm 66 has been rotated counterclockwise, as viewed in Figure 6, approximately thirty degrees.

The pressing of the scavenger lever 59 will transmit a rotating motion to the shaft 64 through the action of the fork 63 upon the pin 65 and arm 66 causing the sweep arm 12 and said arm 66 to rotate counterclockwise as viewed in Figure 7. This same movement of the scavenger lever 59 simultaneously causes the cam 62 to engage and raise the cam roller 41 and thereby swing the yoke 37 back and away from the rear side of the plate 1. This retraction of the yoke 37 carries the magnet 10 away from the plate 1 thus releasing any ferromagnetic coin or slug which said magnet may have been holding at the upper end of the coin passage 4. The retraction of the yoke 37 also causes the withdrawal of the coin rail 9 from its position at the bottom of the coin passage 4, thereby allowing any ferromagnetic coin released by the retraction of the magnet 10 to drop down into the undersize coin chute 32 and slide out of the selector device in the same manner as a rejected undersize coin. The motion of the sweep arm 12 positively dislodges any coin or slug which may have been attracted to the face of either magnet 11 or 16 and sweeps such coins into the coin rejection passage 7, as illustrated diagrammatically in Figure 7 by the broken line outline of a coin at 66.

As above noted, after approximately the first thirty degrees of rotation of the crank arm 66, the cam 60' engages the cam roller 33 and forces the same to move to the left, as viewed in Figures 2 and 9, thus causing the front plate 2, which carries the undersize coin guide or chute 32 on which the roller 33 is mounted, to pivot upon the hinge pin 39 and move a limited distance outwardly and away from the plate 1. This opening of the front plate 1 allows any coin which may have become lodged in any of the various coin passages to drop downwardly into either the undersize coin chute 32 or into the rejection passage 7. It also allows any perforated coin retained by the retainer finger 54 to slide off of said finger and drop vertically into the rejection passage 7, thus effectively clearing the device of all coins arrested therein.

Upon the release of finger pressure from the scavenger lever 59, the action of the torsion

spring 38 and the mutual attraction of the magnets 17 and 18 cause all the parts to return to their normal positions, thus completing the scavenging operation. The returning action may be aided by the use of a torsion spring 67 mounted about shaft 64 between the crankarm 60 and the plate 1, one end of said spring being fixed to the plate and the other end thereof being fixed to the arm 60.

The rejected coin guide 85 and the rejection passage 7 may communicate with a single chute (not shown) for conveying all rejected coins to a receptacle accessible to the operator, and the coin passage 3 may be positioned over a cash box or over a chute for conveying accepted coins to a coin controlled mechanism (also not shown) and thence to a cash box.

Underweight coins, which would have a tendency to lodge upon the faces of horseshoe magnets 17 and 18 if permitted to reach the same, may be prevented from gaining entrance to the coin passage 4 by mounting, in any suitable manner above the entrance 3 of said coin passage, an underweight coin rejection mechanism illustrated in Figures 12 to 16. Such mechanism may be incorporated in a coin chute 68, shown as of arcuate form and defined by the sides 69 and 70 and by bottom members 71, leading laterally and downwardly to said entrance to the coin passage 4.

A counterweight plate 72, normally disposed in a horizontal position and forming the bottom of the chute 68 at its lowermost end, is hinged to the side 69 by means of a hinge pin 73 passing through ears 74 on the side 69 and through ears 75 on said plate 72. The weight of the plate 72 is distributed with respect to the pin 73 so that said plate normally rests in the closed position, as illustrated by the Figure 15, and will open only when a coin weighing as much as or more than a U. S. nickel, for example, rolls down the chute 68 and onto the plate 72, tipping the same as illustrated in the Figure 16.

A coin weighing less than a desired amount will roll down the chute 68, across the plate 72, and be rejected through an open end 76 of said chute 68, as illustrated by the Figure 12. Said open end 76 may be connected with a chute (not shown) for conveying rejected underweight coins to a rejected coin receptacle. A striker plate 77 may be mounted, preferably in inclined position, slightly below the plate 72, between said plate and the open end 76, to arrest the lateral motion of coins which drop through the trap into the entrance 3.

The upper end of the chute may be connected by means of screws, or otherwise, to a coin receiver plate 78 which may be mounted in the face of a cabinet (not shown) enclosing the entire coin selector device. Said plate 78 has a slot 79 therein for insertion of coins into the device. The chute 68 is shown as supported from the supporting plate 90 by means of a bracket 80.

The foregoing detailed description has been given for clearness of understanding only, and no unnecessary limitations should be understood therefrom, but the appending claims should be construed as broadly as permissible in view of the prior art.

I claim:

1. In a coin selector embodying a plurality of coin passages formed by a plurality of walls and incorporating a magnet disposed contiguously to at least one of said passages to affect the movement of coins therethrough, a sweep-arm rotat-

ably mounted to move across the face of said magnet and within said passage, a second magnet disposed outside one of said walls and adjacent to a second one of said passages thereby creating a magnetic field within the latter of said passages for arresting the movement of ferromagnetic coins therethrough, one of said walls being movable relative to the other, a movable support for said second magnet, and means comprising

10 externally operable mechanical linkage and actuating means operable thereby and operatively engaged with said sweep arm, said magnet support and said movable wall whereby substantially simultaneously said sweep-arm may be rotated to dislodge coins from the face of said first magnet, the space between said second magnet and its adjacent wall may be momentarily increased to decrease the intensity of said magnetic field within said second passage and thus 15 release coins arrested by said field, and whereby said walls may be momentarily separated each from the other thereby increasing the sizes of said passages and providing space through which coins so dislodged and so released may fall freely 20 from said passages.

2. In a coin selector embodying a plurality of coin passages formed by a plurality of walls and incorporating a magnet disposed contiguously to at least one of said passages to affect the movement of coins therethrough, a sweep-arm rotatably mounted to move across the face of said magnet and within said passage, a second magnet disposed outside one of said walls and adjacent to a second one of said passages thereby creating a magnetic field within the latter of said passages 30 for arresting the movement of ferromagnetic coins therethrough, a coin rail protruding through one of said walls and into said second passage below said magnetic field for supporting 35 coins in said second passage, one of said walls being movable relative to the other, a movable support for said second magnet and said coin rail, and means comprising externally operable mechanical linkage and actuating means operated thereby and operatively engaged with said sweep arm, said support and said movable wall whereby substantially simultaneously said sweep-arm may be rotated to dislodge coins from the face of said first magnet, the space between said 40 second magnet and its adjacent wall may be momentarily increased to decrease the intensity of said magnetic field within said second passage and thus release coins arrested by said field, said coin rail may be momentarily withdrawn from said second passage to discontinue the support 45 of coins therein, and whereby said walls may be mechanically separated momentarily, each from the other, thereby providing space through which coins so dislodged and so released and denied support may fall freely from said passages.

LOUIS F. HEHN.
